DIFFERENTIALLY OPERABLE ACCUMULATING MECHANISM

Earl R. Lawson, Vestal, N. Y., assignor to International Business Machines Corporation, New York, N. Y., a corporation of New York

Application May 24, 1949, Serial No. 95,032

4 Claims. (Cl. 235—61.6)

1

This invention relates to record controlled accounting machines and more particularly to the accumulating devices therein.

The principal object of the invention is to provide simplified control mechanism and circuit connections for the accumulating mechanism. The type of accumulator to which the invention applies is the well known differentially operable accumulator in which the accumulating element or wheel is coupled or clutched to a constantly rotating driving element. A start magnet when energized effects coupling and a stop magnet when energized effects uncoupling, and by controlling the relative times of energization of these magnets the wheel may be advanced to enter any selected digital value.

Heretofore, a single pair of start and stop magnets was provided in each denominational order of the accumulator, and through switching mechanism were controllable during adding operations to enter digits and during resetting operations were effective to advance the wheels to their zero or home positions.

In accordance with the present invention, there is provided in each denominational order a second pair of start and stop magnets, and the circuits are reorganized so that one pair of magnets is controlled for adding or subtracting operations, and the other for resetting and total taking operations. This enables the elimination of switching devices known as "total switch plates" whose function was to adjust the circuits between adding and total taking operations, so that the single pair of magnets would respond to different current sources.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a side elevation view of an accumulator assembly showing two accumulator orders. Some of the parts in the lower order are sectioned and other parts are removed to clearly reveal the totalizing mechanism.

Fig. 2 is a front and sectional view of the accumulators taken along the line 2—2 of Fig. 1.

Fig. 3 is a sectional elevation view of the accumulator taken along the line 3—3 of Fig. 1.

Fig. 4 is a detail view of the tens carry contacts as positioned when the related accumulator wheel is located in the zero position after having passed from 9 to 0.

Fig. 5 is a detail view of the tens carry contacts

2

as positioned when the associated accumulator wheel is located in its 9 position.

Fig. 6 is a wiring diagram of the electrical circuits for controlling the accumulator.

Fig. 7 is a timing diagram showing the period of operation of certain of the electrical and mechanical devices.

A machine of the type to which the invention may be applied is shown and described in detail in the patent of A. W. Mills, No. 2,079,418, granted May 4, 1937. The accumulator thereof, to which the present invention is directed, will first be described as to its structural arrangement and with reference to Figs. 1 to 5.

The gear 10 in each accumulator order is mounted on a bushing 29 (Fig. 2) and keyed to another gear 30 by means of a dowel pin 31 fastened to the bushing. The unit comprising the gears and the bushing is free to rotate constantly on the stud 11. The stud is extended by attaching a shouldered sleeve 32 thereon by a screw 33.

Between the head of the screw and the shoulder on the sleeve is located a hub 34 carrying an accumulator gear wheel 35 and a tens carry disk 36. Thus, the two separate gear units may rotate independently on the stud 11. The unit containing gear 30 is rotated one-half revolution for each cycle of operation of the machine. The accumulator gear 35 is provided with forty teeth. Therefore, one-quarter revolution of this gear represents a complete adding operation of ten steps.

The two gears 30 and 35 are adapted to be clutched together so that the accumulator gear 35 may be driven a differential distance by the drive gear 30. The clutching device includes two pinions 37 and 38 (Figs. 1 and 3) which are held together by a bushing 39 on a stud 40 mounted on a clutching lever 41 pivoted at 42 (Fig. 1).

Pinion 31 is adapted to engage with the gear 30 but the teeth thereon are normally out of engagement with the gear teeth. The other pinion 38 maintains engagement with the teeth on accumulator gear 35. A spring 43 attached to lever 41 urges the lever counterclockwise to clutch pinion 37 with gear 30 for driving, but the lever is prevented from moving by the contact of the end of a horizontal arm thereon with the end of an armature 44 pivoted at 46 and associated with the accumulator magnets D and D¹, the armature being held in such a position against a stop stud 47 by a spring 45.

When either of the magnets D or D¹ is energized, attracting the armature, the lever 41 is released and then the spring 43 rocks the pinion 37 into mesh with the gear 30.

An adding operation in the accumulator is

effected by the sensing of an amount perforation in one of the data columns of the record card 1 (Fig. 6) by the respective sensing brush 5 to cause energization of magnet D. The pinion 37 is then thrown into mesh with the gear 30 while the latter is rotating. Through the connections between pinions 37 and 38 and gear 35 the accumulator gear is caused to rotate until the zero position on the card reaches the brush, at which time the pinion 37 is thrown out of mesh by a cam 50 (Figs. 1 and 2) which cooperates with the clutching lever 41. This cam is fixed with respect to gears 10 and 30 and thus is constantly rotating with them. As shown in Fig. 1, two cam projections 51 and two projections 52 are provided on the cam 50 because the cam is timed to turn a half revolution for each accumulator cycle. After the pinion 37 is thrown into mesh with gear 30 and commences to rotate gear 35, as soon as the cam projection 51 reaches an arm 52 extending from lever 41, the cam rocks the lever clockwise about the pivot 62 to move the pinion 37 out of mesh with gear 30, so that the accumulating gear 35 is declutched from the driving means and ceases to rotate. The lever 41 is latched in the declutched position by the armature 44.

When the clutching lever 41 is moved counterclockwise to clutching position, an extension on the top of the lever engages a shoulder on a plate 54 which is located properly to stop the lever. An impositive latch or pawl 55 is pivoted at 42 and connected to lever 41 by a pin and slot connection 56. When the lever holds the clutching pinions out of engagement, pawl 55 engages the teeth on gear 35. The pawl also prevents overthrow of the gear as it is declutched. The pinion 38 is provided with an impositive latch 57 pivoted on plate 7.

If it is desired to subtract an amount from the accumulator, the complement of the amount is added to the accumulator. In adding the complement, accumulator magnets D are energized automatically at the nine index position (the units order at the ten position) to mesh pinions 37 with gears 30 and start the wheels rotating. Each wheel continues to rotate until a perforation is sensed, then the gears in the accumulator receiving the complement are declutched. The connections for operating the lever 41 to secure the desired relationship between the clutching of one accumulator and the declutching of the other accumulator will now be described.

A subtraction and cancellation control magnet S (Fig. 1) is energized under control of the record card perforation sensed by the brush 5. A magnet S is provided for each accumulator order and is associated with devices for operating clutching lever 41 to declutch gear 35. A long lever 58 is pivoted at 59 on plate 7 and has one end cooperating with the bottom of an armature 60 associated with magnet S. The armature is pivoted at 61 and held normally against a stop stud 62 by a spring 63. When the magnet is energized, releasing the end of the lever 58, a spring 64 urges the lever in a counterclockwise direction against stop 65 and a pin 66 on the lever is pushed against a latch 67 pivoted at 68. The latch 67 normally engages a shoulder 69 on an arm 70 pivoted at 71.

Another shoulder 72 on the arm 70 is urged towards the horizontal arm on a lever 41 by means of the spring 43 attached to a stud on the arm. The sudden release of the arm 70 after the pin 66 pushes the latch 67 away from

shoulder 69 causes the two parts 70 and 41 to rock clockwise under the urging of the spring 43 connecting the two, thereby swinging the lever 41 in a clockwise direction to declutch the gears. This action is accomplished because spring 43 tends to fold together and shorten. It can shorten only when member 70 and frame 41 are rocked in a clockwise direction. Therefore, when the latch 67 releases the spring, it moves the frame to declutch the gears. The parts 67 and 70 delay declutching a moment after magnet S is energized. The lever 41 is latched in normal position by the armature 44.

At the end of each machine cycle the lever 58 is restored by one of a pair of rollers 73 mounted on a flange of the bushing 29 (Fig. 2). The roller strikes the lower side of the left end of the lever (Fig. 1), rocking it clockwise and latching the right end under armature 60. While restoring, a pin 74 on lever 58 strikes the lower edge of arm 70 and restores the arm, placing shoulder 69 above the latching face on latch 67 and tensioning spring 43 to urge lever 41 in the proper direction for clutching the gears. The parts 67 and 70 provide means for controlling the declutching time, so that a uniform disengagement of the gears is secured during the operation of the machine.

From the foregoing section of the description, it is clear that the accumulator wheels are 30 clutched to the driving gears by means under control of the accumulator magnets D, and they are declutched by the magnets S at differential times during a cycle or by cam 51 at the end of a cycle. During ordinary adding operations, the magnets S are not used, the accumulator wheels being clutched at the differential times by the magnets D and declutched at the zero position by cams 51.

When the machine is set for subtraction control, the magnets D are energized early in the cycle to clutch the accumulator wheels to begin adding the complement of the amount. Then, when a certain amount perforation in the card is sensed, the related accumulator magnet S is 40 energized to declutch the wheel at the differential point.

For effecting carrying or transferring from one order to the next order in an accumulator, a frame 77 pivoted at 78 is adapted to cooperate with the cam faces on the tens carry disk 36 which is attached to the accumulator gear wheel 35 as described hereinbefore. An insulation block 79 secured to frame 77 cooperates with the center blade 80 of a set of contact blades 80, 81 and 82. A finger 83 extending from the frame 77 cooperates with the periphery of the transfer disk 36.

When the accumulator wheel is located in the 60 nine position (Fig. 5), a notch 84 in the disk is in line with finger 83 and allows frame 77 to rock in a counterclockwise direction, permitting the center spring contact blade 80 to rise, closing the contacts 85 between the two upper blades.

If the accumulator wheel passes from the nine to the zero position during an adding operation (Fig. 4), a projection 86 on disk 36 strikes the finger 83 and rocks the frame 77 in a clockwise direction. The block 79 then depresses the center blade 80 below the normal position and closes contacts 87 between the two lower blades. A latch 88 pivoted at 89 cooperates with a shoulder 90 to hold the frame in shifted position after the wheel passes the camming position. A spring 70 91 holds the latch in position until the end of

the adding cycle when one of the rollers 73 strikes the latch and releases frame 77 for movement counterclockwise into normal position as urged by blade 80.

After accumulating, the wheels are restored to the normal zero position, finger 83 rests on the concentric edge of the disk, and frame 77 holds the center blade 80 with both contacts 85 and 87 opened.

Each lower contact 87 is wired in series with the next higher order accumulator magnet D in a manner to be explained more fully hereinafter with reference to the wiring diagram.

The upper contacts 85 are also wired to connect to higher order magnets so that, if a carry impulse is directed to the magnet associated with closed contacts 85, the impulse is carried through them to the next higher magnet. The carry impulses through the contacts 85 and 87 are timed to occur after the cam projection 51 passes the extension 53, so that if a carry is desired the magnet D is energized, releasing lever 41 and clutching the accumulator gear for one step of movement, after which the clutch lever is again thrown out by the engagement of the cam projection 52 with extension 53.

The energization of the units order magnet at the ten rather than the nine position during complement addition has been mentioned before in this specification. The extra unit thus gained fills out the complement to the true tens complement of the number being subtracted. If the number represented on a record card contains a zero in the units column, the rotation of the units order wheel through ten steps of movement will actuate the carry mechanism to induce a carry into the higher order wheel, thus automatically carrying the extra unit to the higher orders to fill out the complement.

Referring now to the circuit diagram (Fig. 6), the card sensing devices are diagrammatically represented and the circuit arrangement is presented in simplified form. When an amount is to be added, the switch 100 is closed to energize the Plus relay R1 and, when an amount is to be subtracted, the switch 101 is closed to energize the Minus relay R2. It will be assumed that the cards 1 are fed past brushes 5 through suitable devices, so that the index point positions 9, 8, 7, 6, 5, 4, 3, 2, 1, 0 pass and are sensed in succession in the usual manner.

With switch 100 closed and relay R1 energized, an adding circuit will be completed when a hole in card 1 is sensed, which is traceable from line 103, card lever contacts CL, contact roller 220, hole in the card, brush 5, plug connection 104, a contacts of relay R1 (shifted), circuit breaker contacts 105 and add magnet D to ground. At the 0 time in the cycle (see Fig. 7), the mechanical knockout cam 51 will declutch the adding wheel, leaving it advanced an amount represented by the value of the hole sensed.

The circuit from brush 5 also extends through connection 104, b contacts of relay R1 and connection 107 to print magnet PM and ground. This magnet positions a type bar, as explained, in the patent referred to, so that the amount added will also be printed on a suitable record sheet.

At the tens carry time, contacts CB14 close and, if for example the units wheel had passed through ten steps and closed its contacts 87, the circuit would be completed from line 103, contacts CB14, contacts 87 in the units order, contacts 106 (now shifted) in the tens order and 78 without departing from the spirit of the inven-

magnet D to ground. This effects clutching in the tens order and, after one step of advance, cam 52 effects mechanical declutching.

For subtracting an amount, switch 101 is closed to energize relay R2 which closes its a and b contacts. Accordingly, contacts CF22 will complete a circuit one point in advance of the 9 sensing time, through the b contacts of relay R2 in the emitter order and contacts 105 to the D magnet in such order. In remaining orders, contacts CF23 will energize the D magnets through similar circuits at the 9 time. Later, when the hole in the card is encountered, a circuit is completed in the units order, for example, from brush 5, connection 104, a contacts of relay R1 (normal) and magnet S to ground to declutch the wheel after advancing an amount representing the 10's complement of the hole value. In other orders this will be the 9's complement.

A parallel printing circuit extends from brush 5, connection 104, a contacts of relay R2 (shifted), connection 107 and print magnet PM to print the true value sensed. Thus, amounts are entered additively or subtractively.

In the foregoing manner, amounts are added or subtracted accordingly as switch 100 or 101 is closed, and it will be assumed that the aggregate of plus items is greater than the minus items, so that the total standing in the accumulator will have a plus value.

In order to read out such total and also to reset the accumulator, switches 109, 110 are closed and switch 111 is shifted to its dotted line position. With switch 110 closed, contacts CB23 will complete a circuit from line 103 and plug connections 112 to all the D1 magnets in parallel, and as a result the adding wheels will all be coupled for rotation ten steps in advance of the zero point in the cycle.

Just before the 9 point, contacts CB30 close to energize relay R3, shift its a contacts and hold them shifted for the period indicated in Fig. 7. Contacts CB13 will transmit a series of impulses at each digit entering time, as indicated, to the 10's carry contacts 87.

Assuming that, for example, the units order stood at 4, the initial energization of its magnet D1 would have coupled the wheel for rotation and six steps or points of advance would cause it to pass from 9 to 0 setting, incidentally closing contacts 87. This closure of contacts 87 would be concurrent with the closure of contacts CB13 at the 4 time and a circuit is then traceable from line 103, through contacts CB13, switch 111 (shifted), contacts 87 in the units order, a contacts of relay R3 in the units order, and stop magnet S1 to ground. Magnet S1 causes uncoupling of the adding wheel leaving it at its 0 or home position. At the same time, there is a circuit from line 103, contacts CB13, switch 111, contacts 87 in the units order, connection 113 to print magnet PM to interrupt the type carrier with its 4 type in printing position.

Similar parallel circuits occur in all other orders, with interruption of rotation of such wheels occurring when they reach 0 with accompanying print of the total.

While there have been shown and described and pointed out the fundamental novel features of the invention as applied to a single modification, it will be understood that various omissions and substitutions and changes in the form and details of the device illustrated and in its operation may be made by those skilled in the art without departing from the spirit of the inven-

tion. It is the intention, therefore, to be limited only as indicated by the scope of the following claims.

What is claimed is:

1. A denominational order of an accumulator comprising a driving element, a driven element, coupling mechanism therebetween, a pair of magnets, each separately effective upon energization to cause the coupling mechanism to connect the driven element for operation by the driving element, a second pair of magnets each separately effective upon energization to cause the coupling mechanism to disconnect said driven and driving elements, entry control means for causing energization of one of each pair of magnets in succession to enter a digital value into the driven element, and reset control means for causing energization of the other of each pair of magnets in succession to reset the driven element.

2. A denominational order of an accumulator comprising a driving element, a driven element, coupling mechanism therebetween, a pair of magnets, each separately effective upon energization to cause the coupling mechanism to connect the driven element for operation by the driving element, a second pair of magnets, each separately effective upon energization to cause the coupling mechanism to disconnect said driven and driving elements, entry control means for causing energization of one of said pairs of magnets to cause coupling of the driven element, means controlled by the driving element for rendering the coupling mechanism subsequently ineffective, reset control means for causing energization of the other of said pair of magnets to cause coupling of the driven element, and means controlled by the driven element when it reaches a reset position for rendering the coupling mechanism ineffective.

3. A denominational order of an accumulator comprising a driving element, a driven element, coupling mechanism therebetween, a tens carry

5

10

20

25

30

40

device, a pair of magnets, each separately effective upon energization to cause the coupling mechanism to effect a driving connection between said elements, means coordinated with the driving element for effecting uncoupling at a predetermined point in the operation of the driving element, a first control means for causing energization of one of said magnets at differential times in advance of said uncoupling operation, whereby the driven element will be advanced differential amounts, a second control means for causing energization of the other of said magnets at a second predetermined point in the operation of the driving element, and means controlled by the tens carry device for effecting uncoupling when the driven element passes through a zero position, and means for selecting either of said control means for operation.

4. In a cyclically operable accumulating mechanism of the type wherein the digit entry in an accumulator element is initiated by an impulse transmitted to a start magnet and is terminated by an impulse transmitted to a stop magnet, the combination therewith of a second start magnet and a second stop magnet for initiating and terminating an entry by impulses transmitted thereto, respectively, a first impulse source for energizing the first pair of magnets, a second impulse source for energizing the second pair of magnets, and devices for selectively rendering either impulse source effective.
